UNITED STATES PATENT OFFICE.

CARLON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR TREATING OILS.

Application filed July 9, 1917. Serial No. 179,388.

This application is a continuation in part of my application Ser. No. 162,233, filed April 16, 1917.

This application refers more particularly to an apparatus for converting relatively heavy hydrocarbons into lighter hydrocarbons.

Among its salient objects are to provide an apparatus for carrying out a process in which the oil is positively circulated through the heated zone so as to subject it to the action of uniform heating for a maximum period of time, while, at the same time, permitting the vapors to pass freely to the condenser; to provide an apparatus in which the danger due to local overheating arising from carbon deposits in the apparatus is obviated by causing the carbon to be precipitated and deposited at points remote from and outside of the heated zone of the combustion gases; to provide an apparatus for carrying out a process which can be run either as a continuous process or as a batch process and if desired, in the same apparatus; to provide an apparatus in which a relatively rapid circulation of the oil through the heating zone is obtained; to provide an apparatus in which the partially converted vapors are condensed and returned to the heating zone; to provide an apparatus in which the incoming fresh oil is preferably preheated by means of the outgoing vapors acting in effect as a heat interchanger; to provide a novel apparatus for carrying out the improved process and in general to provide an improved apparatus of the character referred to.

In the drawings:

Fig. 1 is a side elevation of my improved apparatus suitable for carrying out the process.

Fig. 2 is a side elevation of the still on an enlarged scale with parts broken away and shown in section to bring out details of construction.

Fig. 3 is a front elevation of the condenser on an enlarged scale, the view of the condenser being taken at right angles to that shown in Fig. 1 and also showing the receiving tank.

Fig. 4 is a top plan view of the bulk supply drums and pipe connections.

Fig. 5 is a fragmentary end view of the construction shown in Fig. 4.

Referring to the drawings—1, 2, 3 and 4 designate the supply drums which may be

of any suitable number and are preferably of the horizontal boiler type. 5 designates the furnace of any suitable construction, within which is mounted the still proper designated as a whole 6. This still or retort consists of a cylindrical upper drum 7 and a pair of lower drums 8 and 9, the upper and lower drums being connected by means of tubes 10, which are fitted in suitable heads in the drums in a well known manner. The tubes which extend into the drum 8 are separated from the tubes leading to the drum 9, by a fire arch or bridge wall 11. The arrangement is such that the gases of combustion from the fire box of the furnace 5 are compelled to pass up over the bridge wall and down to the bottom of the stack 12. The stack is controlled by suitable dampers 13. The lower drums 8 and 9 are provided with hand hole plates 14, so that they can be cleaned out and the upper drum 7 is provided with a similar hand hole plate 15. The upper drum 7 is also provided with a pressure gauge 16, liquid gauge 17, and safety valve 18. On the upper end of the drum 7 is mounted a combined reflux condenser and heat interchanger 19. The member 19 consists of upper and lower headers 20 and 21 connected by tubes 22, through which the vapors pass, the lower header 21 being connected by pipe 23 to the drum 7. The headers are surrounded with a shell 24. The incoming oil to be treated is admitted to the chamber 24 through the supply pipe 25 near the lower end of the chamber and is taken out near the upper end of the chamber through pipe 26. The pipe 25 leads to a pump 27, which is connected through pipe 28 to any suitable source of supply such as an oil line or oil tank. The delivery pipe 26 leads to the manifold 29, which is connected by means of branch pipes 30 to the front ends of the supply drums 1, 2, 3 and 4. Valves 31 and 81 are interposed in the feed line 26 and similarly the branch feed pipes 30 are each provided with a valve 32 so that any one or more of the drums can be cut out of the feed line.

Describing now the manner in which the oil circulates from the large drums 1, 2, 3 and 4 through drums 8 and 9, and pipes 10, then back to the larger drums again, the oil is drawn from the bottom of the drums 1, 2, 3 and 4 by means of lines 42. These lines lead into the manifold 41 which is connected to the inlet pipe 74 of the pump 110.

75, placed in the line at this point to obtain a positive and controllable circulation of the oil. A valve 72 is inserted in the line between the manifold 41 and the T connection and elbow at 73 which leads to the inlet pipe 74. From the pump 75 the oil is discharged through the lines 76, 83 and 40 and into the lower drum 9. From this drum the oil circulates through the tubes 10 and finds 10 its way out through a discharge pipe 36 in the bottom of the drum 8. Thence through the lines 36 and 35 and back to the supply drums by means of lines 34. While the oil is making the circuit, valve 78 must be closed in 15 order that the oil will not enter the line 79, thereby causing a back pressure on the oil flowing into the inlet of pump 75. It is also essential that valves 43, 72, 77 and 80 are open to allow a free circulation through 20 the system. During this method of circulation, valve 82 is kept closed and valve 81 open and the oil supply is fed to the drums 1, 2, 3 and 4 through lines 26, 29 and 30 as previously explained.

25 If it is desired to cut out the larger drums 1, 2, 3 and 4 for any reason, it may be done in the following manner. By means of the pump 75, the oil can be kept circulating through the drums 7, 8 and 9 and the tubes 20 10 without passing through the larger drums. This is arranged by closing valves 72 and 80 and allowing valves 77 and 78 to remain open. The oil is then discharged from the pump through the lines 76, 83 and 25 40 into drum 9, through tubes 10, into drum 8 and back by means of lines 36 and 79 to the inlet of the pump. If this method of circulation is used the system can be arranged so that the oil supplied by pipe 26, 40 instead of being put into the drums 1, 2, 3 and 4 can be run directly into drum 7 by closing valve 81 and opening valve 82.

When the process is operated as a continuous process, means must be provided 45 for continuously removing the heavy residuum from the supply drums 1, 2, 3 and 4. This is accomplished by means of the header 44, which is connected to the rear ends of the drums about midway their height by 50 means of branch pipes 45, controlled by valves 46, 47 and 48. The object of having the triple sets of valves is that by shutting the valves 46 and 48 on any drum and opening the valve 47, on said drum, this drum 55 is cut out and bypassed. By opening the valves 46 and 48 and closing the valve 47 the drum is admitted into the series.

In certain instances, it may be desirable to connect the supply tanks in series instead 60 of in multiple so as to form in effect, one large supply tank. This is accomplished as follows: The valves 43 in the pipes 42 leading to drums 1, 2 and 3 are shut. The valve 43 in the pipe 42 leading to drum 4 65 is left open. Valves 46 and 47 on drum 4

are closed. Valve 48 on drum 4 is left open. Valves 46 and 48 on drums 2 and 3 are left open while valves 47 in drums 2 and 3 are closed. Valve 46 in drum 1 is left open while valves 47 and 48 are closed. The circulation is then as follows:

From drum 8 through lines 36, and 35, and manifold 34 to lines 37 and 38, thence into drum 1. Out through valve 46 into manifold 44 and into drum 2, through valve 48, 75 out through valve 46 into manifold 44 and into drum 3 by means of valve 48, thence into drum 4 through valve 46, manifold 44 and valve 48. The oil is then drawn from the bottom of the drum 4 by means of pipe 42, 80 through the suction pump into drum 9.

Where the process is operated as a continuous one, the drums 1 and 2, 3 and 4 are kept practically full. To prevent the gas pocket which is usually formed in the drums, 85 each is provided with an outlet 49, leading to manifold 50, each pipe 49 having a valve 51. The manifold 50 leads to any suitable storage.

From the top of the header 20 of the reflux condenser, a pipe 52 leads to a water condenser 53, the latter being mounted in a suitable water tank 54. The coils of the condenser 53 are so positioned as to have a gradual incline downwardly to the receiving tank 55. Water is supplied to the tank 54 by means of supply pipe 56 having a valve 57. The tank 54 also has a water overflow pipe 58. In the pipe 52 is interposed valve 59. The receiving tank 55 has a safety valve 60, pressure gauge 61, glass liquid gauge 62, and gas blowoff pipe 63, controlled by valve 64. The lower end of the receiving tank 55 has a distillate discharge line 65, controlled by valve 66. Preferably a water drawoff 67 is provided having a valve 68. From the foregoing it will be seen that pressure can be maintained on both the still and condenser and regulated by means of valves 64 and 66. At the start of the process, to 110 get up initial pressure, the valve 59 may be closed. The reflux condenser is provided with pressure gauge 69 and the pipe 52 with a pyrometer 70. The supply drums are also provided with liquid level gauges 71, to show 115 the level of the liquid in the drums.

The operation of the apparatus is as follows: Oil, whether it be crude petroleum, distillate or residuum is pumped into the supply drums which are connected either in multiple or in series as may be desired, and into the drums 7, 8 and 9 in sufficient quantity to fill the drum 7 up to the level designated by line A. As the oil in the retort is heated, the vapors will pass up through the reflux condenser and thence over into the receiving tank through the gooseneck and water condenser. The heavier or partially converted vapors will be condensed in their passage through the reflux condenser and will fall 120 125 130

back into the retort and be again subjected to the cracking action. The incoming crude oil acts as a condenser to return these heavier vapors to the retort. If the process is operated as a batch process the reflux condenser can either be used as an aerial condenser or it can be cooled in some other suitable manner. The unvaporized oil which passes through the retort is, of course, returned to the supply drums and again delivered to the retort and can be subjected to the heat of the cracking action. In practice this circulation takes place very rapidly so that the oil is subjected to the heating action for relatively prolonged periods. The supply drums are preferably insulated and the circulation is so rapid that the oil in passing from the lower end of the retort back to the drums is only slightly cooled. The temperature and pressure varies with the character of the oil being treated. A temperature of from 650° F. to 1000° F. is suitable and a pressure of from 50 to 500 pounds to the square inch will probably be ample. The oil can be circulated rapidly or slowly by merely regulating the speed of the pump.

I claim as my invention:

1. In an apparatus for cracking oil, a furnace having heating flues therein, substantially straight vertical heating pipes extending through said heating flues, a supply tank, a connection between said heating pipes and tank, a liquid forcing means and connections from said tank and heating pipes to said means.
2. An apparatus for cracking hydrocarbons comprising a tank for holding a body of oil, a furnace, a series of small vertical straight pipes in the furnace, means for forcing oil from the tank to the lower ends of said pipes and return connections from the upper ends of the pipes to the tank.

CARBON P. DUBBS.
